PATENTED MAY 24 1870

FIG 1

FIG 2

FIG 3

FIG 4

FIG 5

United States Patent Office.

JOHN W. STILL, OF SAN FRANCISCO, CALIFORNIA.

Design No. 4,067, dated May 24, 1870.

DESIGN FOR A GATE-LATCH.

The Schedule referred to in these Letters Patent and making part of the same.

I, JOHN W. STILL, of San Francisco, county of San Francisco, in the State of California, have invented and produced a new and original Design for a Gate-Latch, of which the following is a specification.

My design consists of a straight, or nearly straight, bar, having on one end a loop or open handle extending out on one side of the direction of the bar, and on the other end a similar loop or open handle extending out on both sides of the bar, this last-mentioned handle having a hook or catch, C, formed on its outside near the bar, the peculiar conformation of

the whole being as represented, and marked A, in Figures 3 and 5, in the accompanying drawings.

What I claim, and desire to secure by Letters Patent, is—

The design for a gate-latch herein described and shown.

In witness whereof I have hereunto set my hand and seal.

Witnesses: JOHN W. STILL. [L. S.]

J. L. BOONE,

GEO. H. STRONG.
